(57) **CLAIM**

The ornamental design for a paddling machine, as shown and described.

DESCRIPTION

FIG. 1 is top and rear perspective view of an embodiment of a design for a paddling machine;

FIG. 2 is a top plan view of the embodiment of a paddling machine shown in FIG. 1;

FIG. 3 is a bottom plan view of the embodiment of a paddling machine shown in FIGS. 1 and 2;

FIG. 4 is a rear elevation view of the embodiment of a paddling machine shown in FIGS. 1-3;

FIG. 5 is a front elevation view of the embodiment of a paddling machine shown in FIGS. 1-4;

FIG. 6 is a left elevation view of the embodiment of a paddling machine shown in FIGS. 1-5;

FIG. 7 is a right elevation view of the embodiment of a paddling machine shown in FIGS. 1-6; and,

FIG. 8 is a top and rear perspective view of the embodiment of a paddling machine shown in FIGS. 1-7, with a broken line environmental showing of a paddle, resistance mechanism, and user.

The portions of the drawings shown in broken or phantom lines, including the paddle and resistance mechanism shown in FIGS. 1-8 and the user shown in FIG. 8, illustrate environment as well as features of the design that form no part of the claim.
